UNITED STATES PATENT OFFICE.

MILAN C. BULLOCK, OF CHICAGO, ILLINOIS.

ROCK OR EARTH DRILL.

SPECIFICATION forming part of Letters Patent No. 443,819, dated December 30, 1890.

Application filed March 16, 1888. Serial No. 267,293. (No model.)

To all whom it may concern:

Be it known that I, MILAN C. BULLOCK, of Chicago, in the county of Cook and State of Illinois, have invented certain new and useful Improvements in Rock or Earth Drills; and I do hereby declare that the following is a full, clear, and exact description thereof, reference being had to the accompanying drawings, and to the letters of reference marked ⁵ thereon, which form a part of this specification.

This invention relates to a rock-drilling machine which, besides other features of improvement, accomplishes the insertion of the casing into the hole at the same time that the ¹⁵ drill or reamer is cutting the hole.

The invention here set forth consists in various matters hereinafter described and claimed, and illustrated in one practical form ²⁰ in the accompanying drawings.

In the drawings, Figure 1 is a front elevation of a machine embodying my improvements. Fig. 2 is a vertical section from front to rear in the line 2 2 of Fig. 1. Fig. 3 is a side elevation of a bent water-feed tube and its connection with the upper end of a section of a tubular drill-rod which is driven by the machine. Fig. 4 is a vertical section of said water-feed tube and its connection with the ²⁵ tubular drill-rod. Fig. 5 is a side elevation of the swiveled frame of the machine with the driving mechanism connected therewith, a portion of the shell of the swivel-head being broken away to reveal particularly the feed ³⁰ mechanism contained therein, and the supports of the horizontal shafts of the feed mechanism being shown in vertical section from front to rear. Fig. 6 is a rear view of the swivel-frame and generally of the matters ³⁵ shown in Fig. 5, so far as visible from the rear exterior, certain concealed parts being shown by dotted lines. Fig. 7 is a horizontal section in the line 7 7 of Figs. 1, 5, and 6, but on the scale of Figs. 5 and 6. Fig. 8 is a vertical section in the indirect line 9 9 of Fig. 7. Fig. 10 is a vertical section in the line 10 10 of ⁴⁰ Figs. 1 and 11, the section of Fig. 10 being taken in the same plane in which the section of the bearings is taken in Fig. 5 and on the

same scale. Fig. 11 is a transverse section of parts shown in Fig. 10, taken upon line 11 11 of said figure. Fig. 12 is a fragment of the ⁵⁵ hollow shaft and of the sliding key-shaft shown in side view in the upper part of Fig. 10. Fig. 13 is a central vertical section running from front to rear in the line 13 13 of Fig. 1 through the parts embracing the feed-screw, including the vertically-movable ⁶⁰ splined clutch seen in Fig. 1 and the other parts below said clutch, being on the same scale as Fig. 5. The feed-screw is shown in side elevation. Fig. 14 is a central vertical ⁶⁵ section of the lower end of the feed-screw, shown in side elevation in Fig. 13, and of a swiveled chuck attached thereto and of a fragment in section of the casing attached to the swiveled chuck. Fig. 15 is a side elevation of the machine-frame or swivel-head, together with the adjacent parts of the engine-frame which supports it.

A is the swivel-plate or back plate of the swiveled frame, mounted, usually, on an engine-frame to turn on an axis coincident with that of the engine crank-shaft B, which is the only part of the engine or motor mechanism here shown. To the swiveled plate A is hinged the swivel-head A' in the usual manner, ⁷⁵ *a* in this instance being the hinge, and *a'* the locking device by which the head A' is fastened back against the plate A when the machine is ready for work. The head A' constitutes a frame-work for the support of the mechanism which sustains, guides, and operates the drill-rod and the feed-screw. The swivel-head is here shown as a shell open at the front, the top plate of which, made heavy and bossed, is lettered A². The bottom plate there- ⁸⁰ of is marked A³. From the ends of the top cross-plate A² rise the parallel guide-pillars A⁴ A⁴, tied together at the top by a cross-girt ⁸⁵ *a*² and having fitted thereto a sliding cross-head A⁵. In this cross-head is rotatably ⁹⁰ mounted a sleeve E, carrying a fixed pinion *e* below and a driving-chuck E' above the cross-head. The chuck E' is of the usual or any suitable construction adapted to seize and turn the drill-rod C. ⁹⁵

C², Figs. 3 and 4, is a bent water-feed tube which is connected with the upper end or section of the tubular drill-rod C by a packed joint C³, constructed in the usual manner to

allow the rod to freely turn while the pipe C² remains stationary.

Below the pinion e the sleeve E also carries a roller thrust-bearing E², (best shown in Fig. 8,) constructed to take either an upward or a downward thrust and provided in its lower end with a screw-thread to take the upper end of the tubular feed-screw D.

F is a feed-nut or interiorly-threaded sleeve 10 (see Fig. 9) fitted to the thread of the feed-screw D and rotatably supported in the cross-plate A² of the swivel-frame. The lower end of the feed-nut is provided with a flange f, having marginal notches f', and also with 15 clutch-teeth f². Below the feed-nut a clutch-sleeve G embraces the feed-screw, being provided with teeth g g' on its upper and lower ends, respectively. This clutch is provided with a spline or feather which fits a longitudinal feather-way d in the feed-screw, and 20 therefore rotates or is rotated by said screw.

The clutch-sleeve G is allowed a vertical movement, which is given it by means of a hand-lever G', Fig. 1, the fixed fulcrum of 25 which is beneath the notched margin of the flange f on the sleeve-nut F. The hand-lever is provided with an arm G², the end of which is adapted to enter a notch f' in the flange f and will do so when the clutch-sleeve is depressed to or below its mid-position.

G³ is a set-screw device of obvious construction, by which the hand-lever and clutch-sleeve may be locked in any desired position.

Below the clutch-sleeve G the feed-screw D 35 is embraced by a non-threaded loose sleeve or hub H, which carries a worm-wheel H', and the upper end of said worm-wheel hub is provided with clutch-teeth h, with which the clutch-teeth G' on the sleeve G may be engaged. Finally, below the worm-wheel hub H the feed-screw D is embraced by a non-threaded but splined sleeve I, which rotates 40 in a bearing in the bottom plate A³ of the swivel-frame A' and carries a fixed pinion I'. (See Fig. 13.)

Back of and parallel with the feed-screw D is rotatably supported a driving-shaft J, Figs. 1, 2, 5, and 6, having its upper bearing in the cross-girt a² at the top of the guide-pillars A⁴ 50 and its lower end stepped in the stirrup J', Fig. 5. The shaft J is provided with a fast beveled pinion J², which meshes with the pinion B' on the engine-shaft B. It is also provided with a sliding pinion J³, which rotates 55 with the shaft by means of a spline, Fig. 2, and which meshes with the pinion e, that drives the drill-rod chuck. The hub of said pinion J³ rotates in the cross-head A⁵. Said shaft J is further provided with a loose pinion J⁴ in position to mesh with the pinion I' 60 below the swivel-head.

J⁵ is a clutch splined on the shaft J below the pinion J⁴ and adapted to engage with the hub of said pinion, as indicated in Fig. 6, to 65 cause the latter to rotate with the shaft. Vertical movement is given to the clutch J⁵ by means of a branched hand-lever J⁶, piv-

oted at j', as shown in Figs. 1, 5, and 6. Finally, the shaft J is provided with a fixed pinion J⁷ immediately above its bearing in 70 the upper cross-beam of the swivel-head.

K is a counter-shaft parallel with the shaft J and supported in long bearings in the upper part of the swivel-head. It carries at the upper end a fast pinion K', which meshes with 75 the pinion J⁷ on the driving-shaft J, and at its lower end within the shell of the swivel-head it is provided with a beveled pinion K², which meshes with a beveled pinion L' on a horizontal feed-shaft L. (Shown in side view 80 in Figs. 5 and 10, in end view in Figs. 1 and 11, and in dotted lines in Fig. 6.)

The shaft L carries three loose pinions L² L³ L⁴, of unequal diameter, as shown in Fig. 5, which mesh with the three pinions M', M², 85 and M³, fixed on the shaft M, which is arranged below the shaft L and parallel therewith, as also shown in Fig. 5. The shaft M is provided with a worm M⁴, which engages the worm-wheel H' on the sleeve H, and 90 said shaft will hereinafter be referred to as the "worm-shaft." As a means of driving the worm-shaft from the shaft L through the medium of either one of the loose pinions L² L³ L⁴, according to the speed which it may 95 be desired to give to the worm-shaft, said shaft L is made hollow, as shown in Fig. 10, and is provided with a slot or opposite slots L⁵ in that portion embraced by the pinions L², L³, and L⁴, as shown in Fig. 12. Into the 100 end of the hollow shaft L is inserted a shaft L⁶, having projections l, which protrude through the slots L⁵, and which are intended to serve as a key for locking either one of the pinions L² L³ L⁴ to the shaft L, according 105 to the position of the key. The pinions L³ and L⁴ are severally provided with annular recesses l' for a part of their thickness, within 110 which recesses the protruding key l may stand and revolve without carrying the adjacent pinion with it; but each of said pinions for the remainder of its thickness is provided with slots or notches l'', adapted to receive the key l, so that when occupied by said key the 115 pinion containing the key is made fast with the shaft and is rotated therewith. The inner or most remote pinion L² of the series is also provided with notches l'' for engagement with the movable key l.

In the sectional view, Fig. 10, the movable 120 key is shown engaged with the smallest pinion L² of the driving series, and said pinion is therefore locked with the driving-shaft L and is rotated therewith, giving the lowest speed provided for to the worm-shaft. By drawing out 125 the key into the next recess l' the shaft L and its key l, together with the key-shaft L⁶, will rotate without carrying either of the pinions, and the same is true when the key occupies the recess in the outer or larger pinion L⁴. 130 By means of this shifting key either of the driving-pinions may manifestly be engaged at pleasure. In order that the key-shaft L⁶ may be drawn out or pushed in while the

shaft L is running, the handle L⁷ on the shaft L⁶ is swiveled thereto, and said handle is kept from rotation by means of a projection l⁸ thereon, which runs in a groove l⁴ in the subjacent part of the frame which forms the bearing for the worm-shaft. (See Figs. 1, 5, and 10.)

With the foregoing description of the gearing and with the understanding that the drill-rod C carries at its lower end a rotary cutter-head C' of any description suitable for either drilling or reaming, and that upon the lower reduced and screw-threaded end D' of the feed-screw D a casing-tube D² may be attached, I will proceed to describe the mode of operation by which the machine does its work.

As before stated, the main horizontal shaft B is rotated by the engine, and its direction of motion for the advance of the drill-rod 20 when the feed-screw D is left-handed, as shown, will be from right to left, as indicated by the arrow applied to said shaft in Figs. 5 and 6. This gives a motion from left to right to the vertical shaft J, as indicated by the arrow applied to the hub of the beveled wheel J² in Fig. 5. The shaft J, through the pinions J³ and e, gives a motion in a contrary direction, or from right to left, to the drill-rod C, as shown by the arrow applied to the pinion e in Fig. 1 and to the drill-rod C in Fig. 2 and in other figures of the drawings.

The feed-screw D has a motion from left to right, (or in a direction opposite to that of the drill-rod,) which is imparted to it through the worm M⁴, worm-wheel H', and clutch G when the latter is lowered into engagement with the worm-wheel hub H. In this position of the clutch G the arm G² on the clutch-lever G' is engaged with one of the notches f' in 35 the flange f on the feed-nut F, by which engagement said feed-nut is held from rotation. The thread on the feed-screw D being left-handed or running downward from right to left, this left to right rotary motion of the feed-screw runs the latter downwardly through the stationary feed-nut, the speed of such downward feed depending upon which pinion of the series L² L³ L⁴ is locked to the shaft L by the sliding key l. In this downward movement of the feed-screw D the drill-rod C is carried down at the same speed through the connection of the feed-screw with the drill-rod by means of the roller thrust-bearing E², sleeve E, and chuck E', Fig. 2. The casing 45 attached to the lower end of the feed-screw D will therefore descend into the hole at the same speed of descent as the drill-rod, so that the hole will be made or reamed at the same time and with the same rapidity that the casing is inserted therein. When the clutch G is in mid-position, as shown in Fig. 1, the feed-nut F is still held from rotation by the lever-arm G², but no rotary motion is given to the feed-screw by the clutch G. A reversed rotary motion, or one from left to right, may, however, be given to the feed-screw D when the clutch G is thus disengaged or in mid-

position by raising the clutch-lever J⁶ so as to bring the splined clutch J⁵ into engagement with the pinion J⁴ and thus cause the latter to 70 rotate with the shaft J. This connection runs the left-handed feed-screw D rapidly upward through the stationary nut F and withdraws the casing and the drill-rod from the hole. Retaining the driving engagement between 75 the pinions J⁴ and I', as just described, and throwing the clutch G upward into engagement with the nut F (which at the same time releases said nut by withdrawing the arm G² of the clutch-lever from engagement with the 80 flange f of said nut) cause the feed-nut to rotate from right to left with the same velocity as that of the feed-screw, and as a consequence the drill and the casing will be rotated in the hole without either upward or downward 85 movement. This single rotary movement is often desirable for the purpose of keeping the drill-rod or casing free in the hole preparatory to its being advanced or withdrawn thereafter, as occasion may require. 90

By connecting the casing D² with the feed-screw D through a swivel-coupling, one form of which is shown at N, Fig. 14, the casing may obviously be thrust down or drawn out without rotation thereof. 95

Manifestly the clutch G cannot be engaged with the worm-hub H at the same time that the clutch J⁵ is engaged with the pinion J⁴, since the rotary motion given to the feed-screw by one of these drivers is opposite that given it by the other. 100

The construction above described, wherein the casing D² is turned in a direction opposite that of the drill-rod, involves an important improvement, for reasons as follows: 105 The casing and drill-rod are necessarily revolved in a direction to tighten the screw-joints connecting the short sections composing said casing and drill-rod. The casing is either forced downwardly with the drill without rotation or turned at a slow rate of speed relatively to the drill-rod, it usually being desirable that the casing should revolve as it descends in order to keep in motion the loose material surrounding it, and this facilitates 110 its descent. It has been found, however, that when the screw-joints connecting the sections of the casing and drill-rod are alike or are both provided with right-hand or left-hand threads the rapid rotation of the drill-rod 115 within the casing produces such a rapid whirling of the water therein as to finally rotate and unscrew the lower sections of the casing to an extent sufficient to cause the complete detachment of the same, and this is liable to 120 take place either when the casing is sunk without rotation or is turned at the usual speed in the same direction with the rod. The detachment of the lower casing-sections in the bored hole is a matter of serious 125 inconvenience, and to avoid liability of such an occurrence I rotate the casing and drill-rod in opposite directions, as above pointed out, of course making the screw-joints of the eas- 130

ing and drill-rod right and left handed to correspond with the direction in which the parts are driven. The action of the rapidly-revolving rod will in this construction tend to 5 tighten the screw-joints instead of loosening the same.

Heretofore separate means have been employed for feeding forward the drill-rod and casing, and another important improvement 10 is involved in the construction hereinbefore described, by which both the casing and drill-rod are fed downwardly by a single feed-screw, which is connected with one of said parts by means of a suitable thrust-bearing, 15 by which the said parts are fed downwardly at the same speed and are at the same time capable of independent rotation.

The main features of construction above referred to may be carried out by the use of 20 an apparatus differing greatly in its details from that herein illustrated. For instance, as far as the turning of the drill-rod and casing in opposite directions and the feeding of both the drill-rod and casing by a single feed-screw is concerned, the gearing for turning 25 the casing may act upon the casing otherwise than through the said feed-screw. Many of the particular details of construction herein shown in themselves embrace important im- 30 provements and are herein claimed as part of my invention—as, for instance, in the machine illustrated the casing is directly attached to and is driven at the same speed as the feed-screw, thereby rendering unnecessary 35 a separate driving-gear for turning the casing, and this feature of the machine is herein claimed as a separate improvement.

Another branch of my improvement relates 40 to the indication by the machine of the relation between the downward force exerted by the weight of the drill-rod and casing to the resistance opposed by the rock or earth to the downward movement of said drill-rod and casing. Such indications are here illustrated 45 as being obtained by means of the vertically-movable feed-nut F, two separate indicators F' F², and intermediate mechanism by which the vertical movements of the feed-nut are transmitted to the pointers on said indica- 50 tors. For this purpose the cross-plate A² of the swivel-head is provided with two downwardly-opening chambers F³ F³, one at each side of the central passage for the feed-nut, on the lower side of said cross-plate, and with 55 two corresponding chambers F⁴ F⁴ in similar positions in the upper part of said cross-beam and opening upwardly. The two chambers of each pair are connected by a passage f³, Fig. 7, and to each chamber is closely fitted 60 a plunger F⁵, which projects beyond the adjacent surface of the cross-plate. A yoke-plate F⁶ is supported by the flange f on the lower end of the feed-nut and bears upwardly against the lower plungers F⁵, and a similar 65 yoke-plate F⁷ rests upon the upper plungers F⁵ and is secured upon the upper end of the feed-nut by means of a nut or similar device

F⁸. As shown by dotted lines in Fig. 9, the lower pair of chambers F³ communicates with the gage or indicator F', and, as seen by dotted 70 lines at the right in said figure, the upper pair of chambers F⁴ communicates with the indicator F². The chambers and tubes connecting therewith are occupied by oil, glycerine, or other similar fluid, and as a result an upward 75 movement of the feed-nut F will advance the pointer on the indicator F', while a downward movement of said feed-nut will similarly advance the pointer on the indicator F². Inasmuch as this feed-nut on the one hand 80 takes the upthrust of the drill-rod and feed-screw, which results mainly from the resistance of the rock to the drill, and on the other hand takes the downthrust of the weight of the drill-rod and the casing, it is manifest 85 that the relations of these two forces which act to give a vertical movement of the feed-nut out of its normal or practically-poised position may at all times be judged by inspection of the indicators. Thus when the hole 90 is just started and but a single length or a few lengths only of drill-rod and casing are connected with the feed-screw the nut will be lifted above its normal or poised position, because the downwardly-feeding force will 95 nearly or practically equal the total resistance encountered by the drill, and the indicator F' will register a correspondingly high figure on its dial. On the other hand, when the hole is deep and the weight of the drill-rod and casing exceeds the force required to 100 overcome the resistance of the rock the feed-nut will stand below its normal or poised position, and the indicator F² will register a correspondingly high figure on its dial. When 105 the drill-rod and casing are of such length as to equal the average resistance of the rock, the indicators will both jump alternately as the resistance varies. The principal utilities 110 of these indicators are, first, their revelation to the operator of the character or hardness of the rock or other material in which the drill is at work, by which he may adjust the rate of feed to the hardness of the rock or to 115 the resistance of the work, and, second, the signal they give of the passage of the drill from one stratum to another and from rock into a cavity. The construction described, wherein a plurality of connected chambers is located in the cross-plate of the frame, has the advantages of allowing the pistons to be made 120 tight, of keeping in practical working order in the continued operation of the machine, and of always giving the fullest indication with an almost imperceptible movement of 125 the feed-nut.

In a prior patent, No. 165,539, dated July 13, 1875, I have shown and described a rock-drilling apparatus having in its frame annular chambers containing annular pistons 130 which are connected with a feed-nut and two pressure-gages connected with the chambers for the purpose of indicating the relation between the downward pressure exerted by the

weight of the drill-rod and the resistance to the advance of the drill-rod caused by the rock and earth. The device for this purpose herein described is in the nature of an improvement on that set forth in the prior patent, which has been found defective in several particulars, but principally from the fact that it is exceedingly difficult to make a tight joint with an annular piston of the character illustrated in said patent. By employing a plurality of small pistons, as herein illustrated, a much more simple and economical construction is obtained and any difficulty with the packing of the pistons is entirely obviated.

A further improvement relates to a support of the swivel-head in addition to that which it derives from the engine-frame. The swivel-plate which directly connects the head with the engine-frame is at the rear part of the swiveled frame, and the weight of the drill-rod and casing when long gives in the overhanging position of these parts a formidable downward strain upon the connection of the frame with the engine in lifting or lowering them. To obviate this difficulty I have shown in Fig. 1 removable legs O O, fitted at their upper ends to the front under surface of the swivel-frame and desirably held in place by bolts o o, as indicated, or in some other suitable manner. They stand in the same or practically the same plane with the feed-screw, and therefore wholly take off the overhanging strain referred to.

The roller thrust-bearing above designated as a whole by the letter E² has, as here shown, the novel feature of giving compressive strain upon the rollers in both upward and downward thrusts. It consists, essentially, of two apertured and relatively-rotatable parts, between the transverse and proximate surfaces of which are inserted friction-rollers, each of the two parts mentioned being extended both above and below the rollers.

The manifest advantage of such construction is to allow of rotation with equal ease whether the thrust be upward or downward. Referring to Fig. 8 as illustrating this bearing-coupling most clearly, the sleeve E (which is the upper of the two principal members of the bearing) is extended downward beyond the rollers E⁴ and is provided above them with the projecting flange E³ and below them with the projecting nut E⁵, each reaching outwardly about half the length of the rollers. The lower member consists of the annular part E⁶, which rises to the upper surface of the nut E⁵ beneath the rollers, and the part E⁷, which at its upper edge extends inwardly to form an annular flange e⁸ over the outer half of the rollers opposite the flange E³. Between the rollers and the upper flanges E³ and e⁸ is inserted a bearing-ring e⁹, and between the rollers and the subjacent parts E⁵ and E⁶ is interposed a similar ring e². In this construction it is plain that the downthrust of the sleeve E through its flange E³ is op-

posed by the part E⁶, while the upward pull of the sleeve E or the downward pull of the casing through the member E⁶ E⁷ is taken by the nut E⁵ and the flange e⁸. In both cases the rollers E⁴ are subjected to compression between the bearing-rings e⁹ and e², and said bearing-rings distribute over the whole length of the rollers the strain which they receive at their outer or inner portions only. The steel ring e⁴ serves merely to confine the rollers E⁴ in place. One of the two shoulders or flanges of each principal member being movable with respect to the other, as indicated by the screw-threads by which said shoulders or parts of each member are shown connected in the drawings, the bearing may be adjusted to any degree of closeness. Such screw-threaded connection of the parts also permits the thrust-coupling containing the rollers and bearing-rings to be joined when made of continuously-annular parts, as shown.

Wishing it to be understood that I am not restricted to the particular devices herein illustrated and described, and reserving the right to claim in a separate application for patent the novel methods and other matters herein set forth but not claimed below, I claim as my invention—

1. A rock or earth drilling apparatus comprising a drill-rod, a casing, gearing which rotates the drill-rod in one direction, and a gearing which rotates the casing in the opposite direction.

2. A rock or earth drilling apparatus comprising a drill-rod, a casing-tube, a vertically-stationary feed-nut, a feed-screw threaded through the feed-nut, a thrust-bearing rotatably connecting the feed-screw with the drill-rod, a gearing applied to rotate the drill-rod, and a gearing which rotates the casing-tube.

3. A rock or earth drilling apparatus comprising a drill-rod, a casing-tube, a vertically-stationary feed-nut, a feed-screw threaded through the feed-nut, a thrust-bearing connecting the feed-nut with the drill-rod, gearing turning the feed-screw, and gearing turning the drill-rod, said feed-screw being attached to the casing-tube so as to both turn and advance the latter, substantially as described.

4. A rock or earth drilling apparatus comprising a drill-rod, a casing-tube, a vertically-stationary feed-nut, a feed-screw threaded through the feed-nut, a drill-chuck having rotatable connection with the feed-screw and engaging the drill-rod, and gearing turning the drill-chuck and feed-screw independently of each other.

5. In a rock-drill, the combination, with guides and a cross-head fitted to move thereon, of a sleeve mounted rotatably in the cross-head, a drill-chuck attached to the upper end of the sleeve, a tubular thrust-bearing or coupling having relatively-rotatable parts attached to the lower end of the sleeve, a tubular feed-screw attached to the lower part of

the thrust-bearing and having the drill extended through it, a feed-nut supported by the frame, and a rotating driving-shaft geared with the sleeve to which is attached the drill-chuck and thrust-bearing.

6. The combination, with a drill-rod, a feed-screw, and a feed-nut supported in a frame and embracing the feed-screw, of a gearing for rotating the feed-screw at a slow speed for the working operation of the drill, a second gearing for rotating the feed-screw at a relatively high velocity for rapidly raising and lowering the feed-screw, and means for connecting and disconnecting either set of gearing with and from the feed-screw at will.

7. The combination, with the frame of a rock-drill, of a feed-nut supported in the frame, a tubular feed-screw threaded through the feed-nut, a drill-chuck rotatably connected with the feed-screw, gearing which rotates the drill-chuck in one direction, gearing for rotating the feed-screw in both directions, and means for throwing said gearing into and out of engagement with the feed-screw.

8. The combination, with the frame of a rock-drill, of a feed-nut supported by the frame, a tubular feed-screw passing through the feed-nut, a gear-sleeve H, rotatably embracing the feed-screw, a clutch splined to the feed-screw and movable into and out of engagement with the gear-sleeve, a gear-sleeve I, splined on the feed-screw, a drill-rod passing through the feed-screw, connected therewith by a thrust-bearing having relatively-rotatable parts, mechanism for rotating the drill-rod, gearing for driving the sleeve H and the sleeve I successively in opposite directions, and means for shifting the gear-connections.

9. The combination, with the frame of a rock-drill, of a feed-nut supported by the frame, a tubular feed-screw passing through the feed-nut, a gear-sleeve H, rotatably embracing the feed-screw, a clutch G, splined to the feed-screw and movable into and out of engagement with the gear-sleeve, a gear-sleeve I, splined on the feed-screw, a drill-rod passing through the feed-screw and connected therewith by a thrust-bearing having relatively-rotatable parts, a casing-tube connected with the feed-screw, mechanism for rotating the drill-rod, gearing for driving the sleeve H and the sleeve I successively in opposite directions, and means for shifting the gear-connections.

10. The combination, with the frame of a rock-drill, of a rotatable feed-nut supported by the frame, a tubular feed-screw passing through the feed-nut, a drill-rod passing through the feed-screw and connected therewith by a thrust-bearing having relatively-rotatable parts, by one of which it connects with the drill-chuck and by the other of which it connects with the feed-screw, a gear-sleeve H, embracing the feed-screw, a clutch G, splined to the feed-screw and movable into

and out of engagement with the gear-sleeve H, a lock by which the feed-nut may be held from rotation when the clutch is engaged with the worm-sleeve, a splined gear-sleeve I on the feed-screw, driving-gear for rotating the drill-rod, variable-speed gearing for driving the gear-sleeve H, and disengageable gearing for driving the gear-sleeve I.

11. The combination, with the frame of a rock-drill, of a rotatable feed-nut supported by the frame, a tubular feed-screw passing through the feed-nut and adapted to be connected with a casing-tube, a drill-rod passing through the feed-screw and connected therewith by a thrust-bearing having relatively-rotatable parts, by one of which it connects with the drill-chuck and by the other of which it connects with the feed-screw, a gear-sleeve 85 embracing the feed-screw, a clutch splined to the feed-screw and movable into and out of engagement with the gear-sleeve H, a lock by which the feed-nut may be held from rotation when the clutch is engaged with the worm-sleeve, a splined gear-sleeve on the feed-screw, driving-gear for rotating the drill-rod, variable-speed gearing for driving the gear-sleeve H, and disengageable gear for driving the gear-sleeve I.

12. The combination, with the frame, of a feed-screw, a rotatable feed-nut, a worm-gear H, rotatable on the feed-screw, a clutch G, adapted to engage both the feed-nut and the worm-sleeve, a lever for moving the clutch G, carrying a locking device for engagement with the feed-nut when the clutch is at or below its mid-position, a splined gear-sleeve I, gearing for driving the sleeve H, gearing for driving the sleeve I, and means for shifting the 105 gearing connections.

13. The combination, with the feed-screw and the vertically-movable feed-nut, of a cross-plate of the frame provided with a plurality of connected upwardly-opening chambers and a plurality of connected downwardly-opening chambers containing a liquid, a plurality of separate circular pistons movably fitted to the several chambers and connected with the feed-nut, and two pressure-gages connected one with the upwardly-opening and the other with the downwardly-opening chambers.

14. The combination, with the feed-screw and with the frame provided with a plurality of upper chambers F³ and a plurality of lower chambers F⁴, of a vertically-movable feed-nut, a plurality of separate circular pistons F⁵, protruding from the chambers, cross-plates F⁶ F⁷, connecting the feed-nut with the pistons, and two gages connected with the several sets of chambers, the latter being occupied by a suitable liquid.

15. In a variable-speed feed-gear for rock or earth drills, the combination, with the drill-rod, feed-screw, and a swivel-head sustaining the same, of an intermediate shaft L, mounted in the swivel-head transversely to the feed-screw and driving-shaft and provided

with a series of loose unequal pinions having interior feather-ways, an annular recess between the feather-way of each pinion and that of the next pinion, a lengthwise-movable 5 part L⁶, provided with a key adapted to engage the feather-ways and to revolve in the annular recess, a counter-shaft mounted in the head parallel with the feed-screw, bevel-gears connecting the counter-shaft with said 10 shaft L, a shaft M, parallel with the shaft L and provided with a reversed series of unequal fast pinions meshed with those on the shaft L, and a worm on said shaft engaged with the worm-wheel on the feed-screw, substantially as described.

16. The combination, with the main frame of a rock or earth drill, of a swivel-head rotatably supported thereon and a removable support or supports fitted beneath the outer part 20 of the swivel-head to aid in sustaining the weight of the drill-rod and other suspended parts.

17. A thrust-bearing for uniting the drill-

rod chuck and the feed-nut or other parts to be similarly connected, comprising two members one having two outwardly and the other two inwardly projecting flanges, bearing-rings engaging the projections of both members, and rollers inserted between the bearing-rings.

18. The combination, with a member E, provided with a fixed flange E³ and a movable flange E⁵, of a member composed of adjustable parts E¹ and E⁷, presenting inwardly-directed flanges or surfaces, rollers E⁴, and bearing-rings e¹ and e² above and below the rollers, said rollers and the bearing-rings being confined between the upper and lower flanges of both members, substantially as described.

In testimony that I claim the foregoing as my invention I affix my signature in presence of two witnesses.

MILAN C. BULLOCK.
